CLAIM

The ornamental design for a console caddy for automobiles, substantially as shown and described.

DESCRIPTION

FIG. 1 is a perspective view of a console caddy for automobiles showing our new design.

FIG. 2 is a top plan view thereof.

FIG. 3 is a side elevational view thereof, the opposite side being a mirror image.

FIG. 4 is an end elevational view as seen from the left side of FIG. 3.

FIG. 5 is an end elevational view as seen from the right side of FIG. 3.

FIG. 6 is a perspective view thereof similar to FIG. 1, but showing the compartment cover swung to an open position.

The bottom of the console caddy is not shown and is substantially unornamental.

FIG.1

FIG. 2

FIG. 3

FIG. 6
